BURNHAM C. STICKNEY, OF ELIZABETH, NEW JERSEY, ASSIGNOR TO UNDERWOOD TYPEWRITER COMPANY, OF NEW YORK, N. Y., A CORPORATION OF DELAWARE.

TYPE-WRITING MACHINE.

1,100,454.

Specification of Letters Patent. Patented June 16, 1914.

Original application filed June 30, 1903, Serial No. 163,704. Divided and this application filed September 3, 1910. Serial No. 580,429.

To all whom it may concern:

Be it known that I, BURNHAM C. STICKNEY, a citizen of the United States, residing in Elizabeth, in the county of Union and State of New Jersey, have invented certain new and useful Improvements in Type-Writing Machines, of which the following is a specification.

This invention relates to typewriting machines, and particularly to so-called "visible" writing machines, in which the line of writing is always in view, and more especially to those of the "front strike" class; and one of its principal objects is to make a more satisfactory disposition of both the margin-governing or regulating mechanism and the ribbon mechanism than has heretofore been made in this sort of machines. Usually the margin mechanism is placed at the extreme front of the machine, where it is in the way and necessitates the use of a cumbersome paper-carriage, or in the extreme rear of the machine where it is inaccessible. By my invention, the margin-gage rack is placed beneath the paper carriage, where it is out of the way, permitting the use of a compact carriage, which is a desideratum; while provision is made for rendering the rack and the tappets thereon accessible when necessary, for adjusting the margin or carriage-alarm when it is desired to set the machine for writing a line of different length. The ribbon spools are also herein shown as mounted beneath the carriage and brought to an accessible position by the same movement that renders the margin-gage rack accessible; although certain features herein shown relating to the ribbon and the carriage mechanisms are shown in my pending application Serial No. 153,024 filed April 17, 1903.

Preferably, and as a matter of further improvement, the means for adjusting the tension of the carriage-propelling spring are mounted beneath the carriage, for compactness, and brought into position of accessibility simultaneously with the margin-gage rack and ribbon spools.

Certain features of improvement herein set forth, particularly the margin mechanism, are also applicable to other makes of writing machines.

My invention consists in certain combinations of devices, features of construction,

and arrangements of parts, which will be 55 hereinafter described and particularly pointed out in the concluding claims.

In the drawings forming part of this specification, Figure 1 is a longitudinal sectional elevation of a front strike writing machine embodying my improvements; one type action being shown in printing position, and the platen being shown in full lines in position for writing lower-case letters, and in dotted lines at upper-case position. Fig. 2 is a detail rear elevation of the bell-ringing and line-locking mechanism. Fig. 3 is a sectional front view of the machine. Fig. 4 is a plan of an adjustable stop for regulating the margin at the left-hand 70 side of the paper. Fig. 5 is an end elevation and Fig. 6 a plan of a three-part adjustable tappet used in sounding an alarm and in successively locking the keys. Fig. 7 is a front view of the machine, showing the carriage 75 tilted up to expose the underside thereof and given access to the adjustable margin-governing tappets, the ribbon spools, and the carriage-spring tension adjusting devices.

Throughout the views like parts are identified by like signs.

The framework of the machine comprises side walls and rear walls forming base 1, and a depressed top plate 3. Forwardly extending type bars 4 are pivoted at their rear ends upon a curved fulcrum-rod 5 mounted in a segment 6, and strike rearwardly against a platen 7. The segment is radially slotted at 8 to receive the type-bar hubs. Each 90 type-bar is provided with a lower-case type 9 and an upper-case type 10, the latter being uppermost when the type bar is in printing position, although this relation may be reversed within the scope of certain features 95 of my improvements, and the type-bars may be otherwise mounted. The type-bars may be operated by any suitable means, as for instance pull-links 11, extending rearwardly and downwardly from the type bars, 100 pendent levers 12 connected between their ends at 13 to said links, a horizontal rod 14 whereon said levers are fulcrumed at their upper ends, horizontal links 15 connected at 16 to the lower ends of said levers and extending forwardly, and key-bearing bell-cranks fulcrumed upon a transverse rod 17 and having pendent arms 18 connected at 19

to said links 15, and forwardly-extending arms 20 bearing the keys 21. Returning springs as 22 may be provided for the type actions. The links 11 may fan out from 5 their front to their rear ends, so that the system of levers 12 may have the same width as the bell-cranks; or, said links 11 may lie in parallel vertical planes, the system of levers 12 being of the same width as the 10 type system, and the links 15 may fan out from their rear to their front ends; or the system of levers 12 may be wider than the type system and narrower than the bell crank system, and both sets of links may fan 15 out.

The platen 7 may be mounted by means of an axle 25 upon a carriage 26, which may be of any suitable construction, but preferably comprises upper and lower bars 27 and 28, 20 the former provided in its underside with a longitudinal groove 29, and the latter in its upper side with a longitudinal groove 30; these bars being connected at their ends by upright bars 31 and 32 formed integral 25 therewith. An integral plate or bar 33 projects forwardly from said connected bars, and at its ends is formed with upright arms 34 and 35 in which the platen axle 25 is journaled. Embraced by the grooved bars 27 30 and 28 is a rail 36, set on edge and provided in its top and bottom edges with grooves 37 and 38, which are provided with bearing balls 39, whereon the carriage runs.

A feeding-in roller 40 may be mounted in 35 rear of the platen upon links 41 rising from ears 42 on the upper carriage-bar 27; and said links may be provided with rearwardly extending lugs 43 for receiving legs 44 of a paper-shelf 45. From the front side of the 40 plate 33 may project forwardly and upwardly extending arms 46, upon whose forward ends is fixed a platen scale 47 provided with an apron 48 upon its rear side contiguous to the platen; the upper edge of said 45 scale being below the printing line upon the platen, and the scale and arms taken together forming a bail which is provided with hinge pintles 49 engaging ears 50 formed upon said plate 33. One or more pressure 50 rollers 51 may be mounted upon an axle 52 mounted at its ends in said arms 46 about midway of their length. Springs 53, Fig. 7, are provided for pressing up said arms and roller, and springs 54 for the rear pressure 55 roller arms. A paper-guiding apron 55 may curve from the rear pressure roller beneath the platen to the forward pressure roller. Paper-guiding fingers 56, extending upwardly in front of the platen and platen 60 scale, and terminating in their upper ends at the top side of the platen, may be adjustably mounted at their lower ends upon a horizontal rod 57, mounted in arms 58 projecting forwardly from the carriage plate 65 33. Said fingers may be attached to collars

59 fitting upon said rod, and may be prolonged at 60 beneath the collars to bear up with some force against the underside of the plate 33, causing the fingers 56 to hug the platen, and preventing accidental displacement thereof along the rod 57. So far as certain of my present improvements are concerned, however, other carriage mechanism may be adopted. Said grooved rail 36 forms part of a movable frame, whereby the paper carriage is enabled not only to run in letter-feeding direction, but also to move in a direction transverse thereto. This frame comprises, in addition to said rail (which may be otherwise formed in some cases) 80 rearwardly extending integral arms 65, which are united at their forward ends by said rail, and a bar 66, which unites said arms between their ends and is integral therewith. Said arms are extended rearwardly from said bar 66, forming ears 67 and 68, which are hinged by pintles 69 in bosses 70 and 71 which project inwardly from the tops of the side walls of the framework 1. The carriage together with its supporting frame may be swung or tilted up about said hinge, so as to expose the underside of the carriage, as at Fig. 7. Said supporting frame may, however, be otherwise formed and otherwise movably supported within the scope of my improvements. 85

In rear of the type bars and below the platen and carriage is mounted upon an axis or shaft 75 a pair of ribbon spools 76 and 77, said shaft being transverse and horizontal 100 and parallel with the hinge 69 of the hinged carriage frame, and said spools being arranged on edge and side by side. The shaft 75 is journaled upon and transfixes the lower end of a downwardly directed arm or hanger 78 integral with the bar 66 of the carriage frame, and having bosses 79 and 80 for suitably supporting said shaft. It will be observed that when in normal position the ribbon spools are inaccessible to the operator, but that when the hinged frame is tilted up to the Fig. 7 position, said spools are brought to an accessible position, for convenience in examining or adjusting or attaching the ribbon, or of detaching or replacing the spools, etc. The depressed portion of the top plate is preferably cleft, as at 81, to make room for the spools, which in normal position dip below said depressed portion. 110 115

For rotating the spool shaft, I preferably use a single pawl 85, operated at every type stroke, and adapted to engage a single ratchet wheel 86, said pawl being provided with a lifting spring 87 and stop 88, and working upon the underside of the ratchet wheel, so as not to lock the hinged carriage frame from swinging up or down. The spools may be slipped onto and off from the shaft 75, being retained by thumb-nuts 89 and 90; and collars 91 and 92 may be fixed 120 125 130

upon the shaft, against which the thumb-nuts may bind the spools; one spool being bound by its nut while the other is left loose, whereby the ribbon may wind back and forth from spool to spool. Other suitable spool-mounting and rotating means may be employed.

From one spool the ribbon 93 is led forwardly and upwardly, as at 94, then across the printing point at the front side of the platen, as at 95, and then back down in front of the platen, as at 96, and thence back to the other spool. At the front side of the platen are provided ribbon-guiding arms 97 and 98, formed at their upper ends with reversely inclined tips 99, 100, the angle of each tip being about 45 degrees, for properly conducting the ribbon across the printing point or field between its ascending and descending portions. Said arms 97 and 98 form part of a ribbon vibrator, being connected at their lower ends by a cross-arm 101, whereby they are supported upon a bent arm 102, which extends backwardly beneath the carriage rail 36, and at its rear end is pivoted by means of a trunnion 103 upon the forward end of an arm 104 projecting forwardly from the frame arm 78 and integral therewith. By this vibrator, the ribbon may be lifted at each type-impression, as will be understood from Fig. 1, to cover the printing point, and then depressed to uncover the same; and since the vibrator is mounted upon the hinged frame, it is carried up with the latter when tilted, thus facilitating the reeving of the ribbon from the spools over the guiding arms 97 and 98. The invention is broad enough to cover the construction of spools and vibrating devices, whether they are mounted upon an independently hinged frame from the hinged carriage frame or not, so as to be swung up with the latter if desired, or so as not to swing up therewith. Said ribbon-vibrator is operatively connected to carriage-feeding mechanism also mounted upon the hinged carriage-supporting frame and cooperating with a rack 106 on the carriage; said feeding mechanism comprising upper detent and feeding dogs 107 and 108, the latter normally in engagement with the rack. The rack is mounted upon the rear ends of hinged arms 109 and 110, the latter being prolonged forwardly of its hinge and provided with a depressible carriage-release key 111. The dogs are mounted upon one end of a rock-shaft 112, journaled in a boss 113 formed upon an arm 114 directed upwardly and forwardly from the shifter-frame bar 66; and said shaft at its other end is provided with an operating arm 115, which at its rear end is pivoted at 116 to a pendent link 117, whereby the arm is operated; said pivot 116 being normally substantially coincident with the

axis of the hinge 69 of the carriage-supporting frame, so that the operation of the escapement mechanism is substantially the same whether the frame is in normal position or shifted up to write capital letters. At its lower end said link is pivoted at 118 to the forward end of a rocker-arm 119, which projects forwardly from a horizontal transverse rock-shaft 120. A universal bar 121 is mounted upon the tops of a pair of arms 122 which rise from said rock-shaft, and lies in rear of the levers 12 of the type-actions, so as to be operated thereby, as at Fig. 1; the described universal-bar frame being provided with a returning spring 123. 70 75 80

The connection between the ribbon-vibrating mechanism and the escapement mechanism consists of a link 124, whose upper end is pivoted to a forward extension 125 of the dog-rocker arm 115, and whose lower end is pivoted to a short arm 126 of the ribbon vibrator. By this means, whenever the dog-rocker is vibrated by the keys, the vibrator is elevated to cause the ribbon to cover the printing point; and upon the return of the carriage-feeding mechanism to normal position, said vibrator drops to permit the ribbon to uncover the printing point. 90

It will be seen that I have combined with the carriage shift frame (65, 66, etc.) a lever 115, 125, for vibrating the ribbon guide 97, 98. Said lever vibrates on said shift frame at 112, and the operating connections for said vibrating lever include the arm 119 and the link 117 which last extends from its pivotal point of connection 116 with said lever 115 to its point 118 of connection with the arm 119, said link 117 lying in a direction which is substantially toward or radial of the pivotal axis 69 of said shift frame, whereby the movements of the ribbon-vibrating lever 115, 125 are substantially the same in different positions of said shift frame (65, 66, etc.) It will also be seen that the vibrating ribbon device 125, 115, or the device 101, 102, 126, 124, 125, 115, is connected at its front end to the ribbon guide 97, 98 and pivoted at its rear portion to the shift frame at 112. An operating lever 119 is fulcrumed in rear of said vibrating device, and link 117 is pivoted to said device and to said lever, the link being arranged to swing slightly back from the Fig. 1 position at the capital shifting operation, and hence to swing crosswise of (or across) a straight line passing through the pivotal axis 69 of said shift frame and the pivotal connection 118 between the link 117 and said operating lever 119. 100 105 110 115 120 125

The carriage may be propelled by a spring-barrel 127, lying horizontally and mounted upon the lower end of a stud 128 depending from the hinged carriage-frame; a strap 129 being attached to the barrel and 130

caught upon a hook 130 upon the carriage bar 28. A ratchet wheel 131 and pallet 132 are provided for adjusting the tension of the spring, the former having a finger-piece 133 and the latter a finger-piece 134, both of which in normal position project downwardly, the ratchet-wheel and pallet being mounted below the spring barrel. When the carriage is tilted up, as at Fig. 7, access is given to the ratchet wheel and pallet, thus facilitating the adjustment of the spring. By mounting the spring barrel and the carriage-feeding mechanism upon the hinged frame, the latter is permitted to swing freely up and down, without liability of deranging the carriage-controlling devices, which always preserve their proper relation to the carriage.

At each stroke of the carriage escapement mechanism the ribbon is fed by means of the pawl 85, the latter being pivoted at its rear end to the top of a rock-arm 135 fixed upon the universal-bar shaft 120.

Preferably advantage is also taken of the hinging of the carriage-support, to enable the latter to be shifted up and down to enable different types to print. Normally the carriage and platen are in the lowermost position, as in full lines at Fig. 1, thereby enabling the lower-case types 9 to print; while by elevating the carriage and platen, as indicated by the dotted circle 7, the upper-case types 10 are enabled to print. The downward movement of the carriage is limited by an adjustable stop 136, threaded forwardly through an arm 137 cast upon the rear wall of the machine framing; the ribbon-spool bearing arm 78 of the hinged carriage-supporting frame being prolonged below the ribbon-spool shaft, as at 138, to bear against said adjustable stop. A shift-lever 139, bearing a key 140, projects forwardly and upwardly from a transverse horizontal rock-shaft 141, journaled in the side walls of the base; and about midway of its length said shaft is provided with an upright arm 142, from which extends rearwardly a link 143, whose rear end has a sliding bearing at 144 in the upper portion of said cast arm 137. Said link is provided with a lug 145, adapted to catch a nib 146 formed upon a hook-shaped stop 147 pivoted at 148 to the lower portion of said ribbon-spool carrying arm 78 in rear of the spool shaft. By depressing the shift key, the shaft 141 and arm 142 thereon are rocked, pulling forwardly the link 143, and by means of the lug 145 and nib 146 swinging the stop down, until said nib is arrested by a stop pin 149. Continued movement of the key, rock-shaft, arm and link then swings the frame arm 78 forwardly and the frame and carriage upwardly about the hinge 69, until the parts are arrested, with the platen in the dotted line position, by the

contact of the hook-stop 147 with the upper end of said cast arm 137 (which of course may be provided with an adjustable stop, if desired.) After the capital type or types are written, the shift key is returned to normal position by a spring 150, while the hinged frame and carriage return by gravity. A spring 151 lifts the hook-stop 147 until it is again clear of the upper end of said cast arm 137, so that it may not contact therewith to interfere with the upward tilting movement of the carriage to the Fig. 7 position. During such tilting movement, the arm 78 and parts thereon are swung forwardly away from their co-operating parts mounted in the machine base; so that at any time the carriage may be given either a limited movement for writing capitals, or a tilting movement to expose the underside thereof.

To provide for writing a line of capitals, I pivot at 152 upon said arm 137 a cam plate 153, whose forward edge, which is eccentric to the pivot, is adapted to engage a bearing-pin 154 projecting from the frame arm extension 138, so that by swinging said cam plate upwardly about its pivot, said arm is driven forward and the hinged frame and carriage elevated to the proper point for writing capitals. For operating said cam plate, I pivot thereto at 155, below the pivot 152, the rear end of a pull-link 156, which extends to the keyboard and is there pivoted at 157 to the upper end of a rock-arm 158, mounted upon a horizontal transverse rock shaft 159 mounted between the walls of the framework. At the left-hand side of the keyboard an upright lever 160 is fixed upon said rockshaft, so that a forward movement of said lever may lift the cam-plate 153 to set the carriage to upper-case position. Forward and rear stops 161 and 162, the former preferably adjustable, may be provided for said lever; and a double-acting spring 163, adapted to bear against a pin 164 fixed upon the lever, may hold the lever against either stop.

The margin-governing mechanism, by which term is meant devices which either positively limit the travel of the carriage or warn the operator that the end of the line is approaching, or both, includes a rack 170, mounted beneath the carriage, being attached by screws 171 to the bottoms of arms or ears 172 depending from the carriage plate 33. Said rack is provided with a series of teeth 173, for enabling the tappets or stops to be fixed at different positions, according to the width of the left-hand or right-hand margin desired on the page of writing.

The means for limiting the return movement of the carriage, and thereby regulating the left-hand margin on the paper, comprises a box-like slide 174, fitted upon the

115

120

125

130

rack and seen at the left-hand of Fig. 7, and also at Figs. 1 and 4, and having formed thereon a stop 175, projecting upwardly from the slide, and in position to contact with the forwardly projecting end of an arbor 176 mounted in the carriage-guiding rail 36 about midway of the length thereof, thereby to arrest the carriage. Said slide is provided upon its underside with a pawl 177, having an upwardly projecting tooth 178 for insertion in any of the notches in the rack, so that any desired width of left-hand margin may be secured. The pawl is provided with a handle 179 and a spring 180 for pressing the tooth 178 into engagement with the rack. By withdrawing the tooth, the slide and stop may be slidden freely along the rack in either direction. The pawl is pivoted vertically upon the slide at 181. The rack is provided upon its underside with a series of graduations 182, and the left-hand edge of the slide 174 may be adapted to coöperate with said graduations, so that when said edge coincides with any graduation on the scale, the first letter of the line of writing will fall beneath the corresponding graduation on the platen scale 47. It will be observed that normally said slide, as well as other tappets upon said rack, are in an inaccessible position beneath the carriage, while the scale 182 is out of sight; but that upon tilting up the carriage, as at Fig. 7, the scale is brought into full view, and ready access is afforded to the slide and its pawl, for adjusting the same along the rack. So far as this feature of my improvements is concerned, any suitable rack and other parts of margin-governing mechanism may be adopted, within the scope of my invention. The novel features pertaining to the margin-governing details herein shown are, however, preferred.

A bell 183, in rear of the rail 36, is hung by a strap 184 upon the bar 66 of the hinged carriage-supporting frame; and a clapper 185 is horizontally pivoted at 186 upon the rear side of said rail, normally resting upon a stop 187. The clapper is lifted by an arm 188, having a long bent finger 189 underlying the clapper, and secured by rivets 190 upon a head 191 formed upon the rear projecting end of the arbor 176, so that by rotation of the arbor, the arm 188 rises and lifts the clapper. It will be observed that the arbor extends horizontally through bosses 192 and 193 formed upon the rear and front sides of the rail, whereby a long bearing is given, to avoid binding. For rotating the arbor to lift the bell-clapper, a tappet 194 is mounted upon a slide 195 mounted upon the rack 170 and resembling the slide 174. Said tappet extends rearwardly (Figs. 5 and 6) from the top of a standard 196 rising from the forward edge of the slide; said standard clearing the forward end of the arbor 176, but said tappet being in position to engage a pallet 197 projecting upwardly from the tip of the arbor. During the letter-feeding movement of the carriage, the tappet engages the pallet and rotates the arbor, lifting its arm and the bell-clapper, until the tappet passes over the pallet, thereby releasing the same, and the bell-clapper being left unsupported, falls and strikes the bell, to notify the operator that the end of the line is at hand. The slide 195 is provided with a pawl 198, having a rack-engaging tooth 199 and a spring 200, whereby it may be adjusted along the rack, to regulate the right hand margin upon the paper.

For locking the type-actions or otherwise rendering the keys ineffective to operate the types, I provide, preferably upon the bell-controlling slide 195, a tappet 201, a short distance to the right of tappet 194, which lies close to the upper side of the slide, but projects sufficiently therefrom to engage a pallet 202 provided upon the underside of the arbor 176, whereby the arbor is rocked in the opposite direction to that already described, thereby producing no effect upon the bell-clapper, but swinging into effective position a tumbler 203, projecting upwardly from the head 191 of the arbor, and preferably integral with the arm 188. Said tumbler is thus brought directly beneath an extension 204 projecting forwardly from the vibrating arm 125 of the carriage-feeding and ribbon-vibrating mechanism, thus preventing operation of said mechanism and hence of the universal-bar and the type actions. Normally said tumbler stands at one side of said extension 204, as seen clearly at Fig. 2, in which position it is maintained by a spring 205, coiled around a reduced portion of the arbor between its ends; said spring being of light tension, and overbalanced by the weight of the bell-clapper, whereby the arbor is returned in one direction by the spring and in the other direction by the weight of the clapper. Said arbor 176 is slidably journaled in said carriage-guiding rail, and its head 191 is engaged by the forked lower end of a rock arm 206, fixed upon a rock-shaft 207 journaled at its end portions in brackets 208 projecting from the rear side of said rail, and provided at its tips with buttons 209, whereby it may be turned. By this means the arbor may be drawn rearwardly to a sufficient extent to enable it to clear the tappets or stops mounted upon the rack 170, thereby enabling a few more letters to be added at the end of the line, or enabling the carriage to run farther upon its return stroke, so that the first part of the succeeding line may be written in the left-hand margin upon the paper. A spring 210 is provided upon the shaft 207, for returning the shaft, together with the arbor, to normal position.

A second or final key-locking tappet 211 may be formed upon the slide 195, at the right of the first line-locking tappet 201, this tappet operating in the same way as the tappet 201, and preventing the writing of any more letters at this end of the line. In some cases, however, this tappet may be omitted. The slide 195 may be of sufficient length to accommodate the three described tappets, or 10 if desired each may be mounted upon a separate slide. Upon its underside the slide may be recessed, and the edge 212 of the recess may serve as an index to coöperate with the scale on the margin-gage rack, for setting 15 the slide to ring the bell or lock the line at any desired point.

Each of the tappets, as well as the stop 175, is preferably formed upon its rear side with an oblique face, as 213 and 214, which 20 during the usual carriage movements cam back the arbor against the tension of the spring 210, out of the path of the tappets or stops, so that the latter are each effective in only one direction.

25 It will further be observed that the rod 57, which supports the collars 59, from which extend the paper-guiding fingers 56, is mounted in a relatively inaccessible position below the platen scale and upon the under- 30 side of the carriage, so that when the carriage is in normal position, it is difficult to reach the collars to slide them along the rod; but that when the carriage is tilted up, said collars are more accessible, and their adjustment is facilitated.

Wide variations may be resorted to within the scope of my invention, and portions of my improvements may be used without others.

40 This is a division of my application No. 163,704, filed June 30, 1903.

Having thus described my invention, I claim:

1. In a front strike writing machine, the 45 combination with types, of a paper carriage, a hinged frame for supporting said carriage whereby the latter may be tilted to expose its underside, said frame having a rail grooved upon its edges and said carriage having 50 grooved bars embracing said rail, balls in said grooves, ribbon spools mounted on said tiltable frame underneath the platen, and means for leading the ribbon to the printing point.

55 2. In a front strike writing machine, the combination of a series of rearwardly striking type bars, a platen, a carriage having grooved bars, a rail having grooved edges, balls in the grooves, a hinged support for 60 said rail, a pair of ribbon spools mounted upon said hinged support, said rail being forwardly of the spools and between the same and the platen, and said spools being mounted below and in rear of the platen, 65 and means for leading the ribbon from the

spools forwardly beneath said rail and up to the printing point.

3. In a front strike writing machine, the combination of a series of rearwardly striking types, a carriage, a frame wherenon said carriage is mounted, said frame comprising a bar extending longitudinally of the carriage, hinged ears projecting from said bar, arms extending forwardly from said bar, and a carriage-supporting rail carried by 70 said arms, an arm extending downwardly from said longitudinal arm, a shaft upon said arm, a pair of ribbon spools mounted on said shaft, and a ribbon vibrator also mounted upon said frame and having a part 75 extending up in front of the platen.

4. In a front strike writing machine, the combination with a series of rearwardly striking types, of a paper carriage, a lift- 80 able frame wherenon said carriage is mounted, a margin governing mechanism mounted beneath the carriage, ribbon spools also mounted upon said liftable frame beneath the carriage, and means for leading the ribbon from the spools to the front side of the 85 platen.

5. In a front strike writing machine, the combination of a series of rearwardly striking type bars, a platen, a carriage wherenon said platen is mounted, a liftable frame 95 wherenon said carriage is mounted, mechanism for adjustably limiting the run of the carriage, sounding an alarm, and locking the type bars, ribbon spools mounted upon said liftable frame beneath said carriage, and a 100 ribbon vibrator also mounted upon said liftable frame and extending to the front of the platen.

6. In a front strike writing machine, the combination of a series of rearwardly striking types, a paper-carriage, a hinged support wherenon said carriage is mounted, margin-governing mechanism beneath the carriage, ribbon spools mounted upon said hinged frame below the carriage, and means 110 for leading the ribbon to the front side of the platen.

7. In a front strike writing machine, the combination with a series of rearwardly striking type bars, of a platen, a carriage, a 115 frame wherenon said carriage runs, a rod mounted at the underside of said carriage, collars adjustable along said rod, paper-guiding fingers extending from said collars upwardly in front of and to the top side of the platen, ribbon spools mounted upon said frame beneath said carriage, means for leading the ribbon from the spools to the front side of the platen, means for vibrating the ribbon to cover and uncover the printing point at each impression, a carriage-propelling spring mounted at the lower side of said frame, and tension-adjusting devices inaccessibly mounted below said carriage spring; said frame being hinged at its rear 120 125 130

side so that it may be tilted up to expose the underside of the carriage and frame, to render said rod, said rack, said spools and said tension adjusting devices accessible.

5. 8. In a typewriting machine, the combination of a paper carriage liftable to expose the under side thereof, said paper carriage being provided with a platen, type bars to strike upon the front side of the platen, ribbon spools mounted beneath the carriage to swing up therewith, and means upon the framework for operating said spools to wind the ribbon.

9. The combination with a carriage and a propelling spring mounted beneath the same and having a tensioning device, and a pair of ribbon spools also mounted beneath the carriage, and means to enable said tensioning device and said spools to be brought together to accessible position.

10. In a typewriting machine, the combination with a carriage, of a margin gage rack mounted beneath the same, a pair of ribbon spools also mounted beneath the carriage, and a carriage-propelling spring also mounted beneath the carriage and having a tensioning device, and means to enable said margin gage rack, said spools and said tensioning device to be brought together to accessible positions.

11. In a typewriting machine, the combination of a carriage shift frame, a ribbon guide, a lever for vibrating said guide pivoted on said shift frame, and operating connections for said vibrating lever including a link which extends from said vibrating lever, said link lying in a direction substantially radially of the pivotal axis of said shift frame, whereby the movements of said vibrator lever are substantially the same in different positions of said shift frame, substantially as set forth.

12. In a typewriting machine, the combination with a platen and a carriage for the platen, of a shift frame which forms the entire support for the carriage and is movable to shift the platen to different printing positions, a ribbon vibrator lever mounted on the shift frame, and means for vibrating the lever the same distance with the carriage and shift frame in both the normal and shifted positions, substantially as set forth.

13. In a typewriting machine, the combination of a carriage shift frame pivoted at its rear portion, a vibrating ribbon guide supported by the shift frame, a vibrating device connected at its front end to the ribbon guide and pivoted at its rear portion to the shift frame, an operating lever fulcrumed in rear of said device, and a link pivoted to said device and to said lever, the link being arranged to swing across a straight line passing through the pivotal axis of said shift frame and the pivotal

connection between the link and said operating lever when said shift frame is shifted, substantially as set forth.

14. In a front strike writing machine, the combination of a series of rearwardly striking type bars, a platen, a carriage, a carriage rail below the platen, a hinged support for said rail, a pair of adjustable ribbon spools mounted upon said hinged support, said rail being forwardly of the spools and between the same and the platen, and said spools being mounted below and in rear of the platen.

15. In a front strike writing machine, the combination with a carriage and a hinged frame whereon said carriage is mounted; said frame comprising a bar extending longitudinally of the carriage, arms extending forwardly from said bar, and a carriage-supporting rail carried by said arms, of an arm extending downwardly from said bar, and a pair of ribbon spools mounted on said arm behind said rail.

16. In a front strike writing machine, the combination of a platen, a carriage whereon said platen is mounted, a frame whereon said carriage is mounted, inaccessible mechanism for adjustably limiting the run of the carriage, sounding an alarm, and locking the type bars, adjustable ribbon spools mounted inaccessible upon said liftable frame beneath said carriage, and a ribbon vibrator also mounted upon said liftable frame and extending to the front of the platen; said frame being liftable to bring said mechanism and said spools simultaneously to accessible positions.

17. In a front strike writing machine, the combination of a series of rearwardly striking types, a paper-carriage, a support whereon said carriage is mounted, ribbon spools mounted upon said support below the carriage, and means for leading the ribbon to the front side of the platen; said support being hinged to bring said margin mechanism and said spools simultaneously to more accessible positions.

18. In a front strike writing machine, the combination with a series of rearwardly striking type bars, of a platen, a carriage, a frame whereon said carriage runs, collars or finger-pieces adjustable along the underside of said carriage, paper guiding fingers extending from said collars upwardly in front of the platen, ribbon spools mounted upon said frame beneath said carriage, means for leading the ribbon from the spools to the front side of the platen, means for vibrating the ribbon to cover and uncover the printing point at each impression, a carriage-propelling spring mounted on said frame, and tension-adjusting devices for said spring inaccessible mounted below said carriage; said frame being hinged at its rear side so that it may be tilted up to expose the

underside of the carriage and frame, to move said collars, said rack, said spools and said tension adjusting devices from inaccessible to accessible positions.

5 19. A typewriter carriage having a normally inaccessible margin gage member, a movable part being provided to render the member accessible, and operable ribbon spools also mounted inaccessibly beneath the carriage and also connected to said movable part to be brought to accessible position by the same movement of said movable part.

10 20. In a front strike writing machine, the combination with a platen and a carriage, 15 of a combined ribbon, margin-gage and carriage supporting frame, having thereon a track for said carriage, and also having thereon manipulable ribbon-spools mounted inaccessibly beneath said carriage; said frame being liftable to bring said tappet and said spools simultaneously to accessible positions.

25 21. In a front strike writing machine, the combination with a platen and a carriage, 30 of a combined ribbon, margin-gage and carriage supporting frame, having thereon a track for said carriage, and also having thereon manipulable ribbon-spools mounted inaccessibly beneath said carriage; means being also provided for leading the ribbon from the spools up to the front side of said platen; said frame being hinged to bring said spools to accessible positions.

35 22. In a front-strike writing machine, the combination with key-operated type-bars, a platen and a carriage therefor, of a combined ribbon, line-lock and carriage-supporting frame having thereon a track for said carriage, and also having thereon inac- 40 cessible mechanism for adjustably limiting the run of the carriage, sounding an alarm and silencing the type bars, said frame also having thereon manipulable ribbon spools mounted inaccessibly beneath said carriage, 45 and said frame being liftable to bring said inaccessible parts simultaneously to accessible positions.

50 23. In a front-strike writing machine, the combination with key-operated type-bars, a platen and a carriage therefor, of a combined ribbon, line-lock and carriage supporting frame having thereon a track for said carriage, and also having thereon inaccessi- 55 ble mechanism for adjustably limiting the run of the carriage, sounding an alarm and silencing the type bars, said frame also having thereon manipulable ribbon spools mounted inaccessibly beneath said carriage, and said frame being liftable to bring said 60 spools to accessible positions; said frame also carrying thereon a ribbon vibrator which is operatively connected to the type-bars and extends to the front of the platen.

24. In a typewriting machine, the combination with a carriage, of an inaccessibly

mounted margin-gage member therefor, manipulable ribbon spools also inaccessibly mounted, and a single part connected to said carriage, said margin-gage member and said spools, to move said margin-gage member and said spools simultaneously to accessible positions while moving the carriage away from normal position.

25. In a typewriting machine, the combination with a carriage and a propelling spring, of a manipulable tensioning device for said spring, manipulable ribbon spools, said tensioning device and said spools being inaccessibly beneath the carriage, and a single device connected to said tensioning device and said carriage, to bring the tensioning device and spools simultaneously to accessible positions while moving the carriage away from normal position.

26. In a typewriting machine, the combination with a carriage and a propelling spring therefor, a manipulable tensioning device for said spring, of a margin gage member, manipulable ribbon spools, said margin gage member, said tensioning device and said spools being inaccessibly mounted beneath the carriage, and a single part connected to said tensioning device, said margin gage member and said spools, to move them all simultaneously to accessible positions while moving the carriage away from normal position.

27. In a front strike writing machine, the combination with a platen and a carriage, of a combined ribbon and carriage supporting frame, having thereon a track for said carriage, and also having thereon manipulable ribbon spools mounted inaccessibly beneath said carriage; said frame being liftable to bring said spools to accessible positions; manipulable collars or finger pieces mounted inaccessibly upon the under side of the carriage and adjustable therealong, and carrying paper-guiding fingers; said collars or finger pieces being brought to accessible positions by the upward tilting of said frame.

28. In a front strike writing machine, the combination with a platen and a carriage, of a frame having thereon a track for said carriage, and also having thereon manipulable ribbon spools mounted inaccessibly beneath said carriage; said frame being hinged to bring said spools to accessible positions; said frame also having thereon a carriage-propelling spring and also inaccessibly manipulable tension-adjusting devices therefor; said tension-adjusting devices being brought to accessible positions by the upward tilting of said frame.

29. In a front strike writing machine, the combination with key-operated type-bars, a platen and a carriage therefor, of a combined ribbon and carriage supporting frame having thereon a track for said carriage, and also having thereon inaccessibile mechanism

for adjustably limiting the run of the carriage, sounding an alarm and silencing the type bars, said mechanism being inclusive of a rack mounted beneath the carriage, said frame also having thereon manipulable ribbon spools mounted inaccessibly beneath said carriage, and said frame being tiltable to bring said tappet and said spools simultaneously to accessible positions; said frame also having thereon a carriage-propelling spring and also inaccessibly manipulable tension-adjusting devices therefor; said tension-adjusting devices being brought to accessible positions by the tilting of said frame.

30. The combination with a ribbon support, of a bar curved at one end below the carriage rail and pivoted at its curved end horizontally with and in the rear of the rail, and carrying at its other end an up-standing ribbon support for vibrating the ribbon.

31. The combination in a typewriting ma-

chine, of a pivoted frame with a ribbon vibrator, a pivoted arm on which said vibrator is carried, a link connected to said arm behind its pivot, a lever pivoted on said frame, to the forward end of which the said link is connected, and a second link connected to the rear end of said lever and to an actuating part.

32. In a typewriting machine, the combination with a ribbon vibrator, a pivoted arm on which said vibrator is mounted, a vibrating frame on which the platen is carried, a universal bar, and a linkage connection passing from the bar through a pivoted connection on the frame to the vibrator, the pivot on the frame being located close to the pivot of the vibrating frame and so that the vibrations of the frame will not sensibly affect the locus of the ribbon vibrations.
